O. CATE, OF BOSTON, MASSACHUSETTS.

Letters Patent No. 76,891, dated April 21, 1868; antedated April 9, 1868.

IMPROVED SASH-FASTENER.

The Schedule referred to in these Letters Patent and making part of the same.

TO ALL WHOM IT MAY CONCERN:

Be it known that I, O. CATE, of Boston, in the county of Suffolk, and State of Massachusetts, have invented a new and improved Sash-Fastener; and I do hereby declare that the following is a full, clear, and exact description thereof, which will enable others skilled in the art to make and use the same, reference being had to the accompanying drawings, forming part of this specification.

The fastener embraced in the present invention is so constructed and arranged in its several parts as to be simple, durable, strong, and effective, and when fastened, secure against being opened from the outside, the construction being such as to enable the use of springs to be entirely dispensed with.

In the accompanying plate of drawings, my improved sash-fastener is illustrated—

Figure 1 being a plan or top view of the same, showing it as applied to a block of wood, and with the parts composing it fastened.

Figure 2, a transverse section, taken in the plane of the line *x x*, fig. 1.

Figures 3, 4, and 5, detail views of the various parts composing the fastener detached from each other.

Similar letters of reference indicate like parts.

A, in the drawings, represents my improved sash-fastener, which is made in two parts, B and C, one, B, of which is to be applied to the lower sash, and the other, C, to the upper sash, in such positions, relatively, that when the two sashes are closed they will be directly opposite to each other.

The part B, to the lower sash, consists of a plate, D, by which, through screws or other suitable fastenings, it is secured to the lower sash. To the upper side of this plate D, another plate, E, is secured, that is raised above the same by a flange, F, along the front edge C, leaving an opening, H, between the back I and end or side, J, edges. K, a slot, in upper plate E, extending from the front to the back edges thereof, or nearly so, through which slot extends the stem L of a knob, M. N, a cross-arm, to inner end of stem L, upon the under side of upper plate E. In cross-arm N, extending in the direction of its length, are slots, a. The slots a are in the same line with each other, but are separated at b.

O, two arms, each bent up at one end, and at the other bent or curved, with a stud or pin, C, fixed in the outer end. These arms are hung at h to a fulcrum-pin of the lower plate, D, and by their pins c are engaged with the slots a of the cross-arm to the spindle, so that by moving the knob M forward or backward in the slot to the plate E, such arms are either swung out into lines parallel with each other and the said slot, or into one and the same direction, or nearly so, or, in other words, in a line at right angles to the said slot, the arms, when in a parallel direction, being brought by their bent-up ends about the rear side, R, to the raised portion, S, (under the top-plate T, of which they pass,) to the part of the attachment applied to the upper sash, where they are fastened, as will be now described.

U, a slide, arranged to move upon the under side of the plate T, being guided between ways, J, of the same, so as to move in a direction toward the rear side R to said plate T. This slide, U, is cut out in its centre, and within and against such cut-out portion acts the cam or arm V, to a spindle, W, arranged to turn in the plate T, this spindle being provided with a milled head, X, suitable for turning it. The cam V is of suitable shape, that when turned either to the right or left, it will throw out or draw in the slide from the back edge to the plate, as the case may be, the slide, when out, by its end shoulders or corners, Z, setting by the bent-up ends of the arms O, if in the position shown in fig. 1, and, consequently, there holding or securing them.

From the above description of my improved fastener, it is plainly obvious that—

First, no springs are needed.

Second, it is simple, efficient, and most perfect and secure.

Third, it cannot be unfastened from the outside, except the sash-frames or the glasses thereof be broken or cut sufficiently for the person to grasp the fastening.

What I claim as new, and desire to secure by Letters Patent, is—

A fastener for window-sashes, &c., composed of an arm or arms, O, and a slide, U, when arranged and combined together, substantially as and so as to operate as described.

O. CATE.
